STEEPING PRESS

Gaston Joris, Paris, France, assignor, by mesne assignments, to Textile and Chemical Research Company Limited, Saint Peter Port, Guernsey, Channel Islands, a corporation of Great Britain

Application August 7, 1947, Serial No. 767,274
In France March 3, 1945

Section 1, Public Law 690, August 8, 1946
Patent expires March 3, 1965

9 Claims. (Cl. 100—50)

1

This invention relates to a steeping press for steeping cellulose pulp sheets in caustic soda solution. More particularly, it relates to a steeping press having means to automatically discharge the cellulose sheets after the steeping operation.

In the preparation of viscose from cellulose pulp sheets, the first step consists in steeping such sheets in a mercerizing solution of caustic soda containing approximately 240 grams of caustic soda per liter. At the completion of the steeping step, the sheets are subjected to a pressing operation to eliminate the excess caustic soda and the hemicelluloses dissolved in the alkaline solution.

The steeping and pressing operations were generally effected in a single apparatus named a "steeping press" which consisted of a long horizontal tank provided with a piston susceptible of axial movement in said tank. The sheets, in small bundles of, for example, 10 to 20 sheets, were placed vertically in the tank between perforated spacer plates designed to insure uniform spacing of the bundles and to facilitate the uniform penetration of the steeping solution. After the press was loaded with the bundles of cellulose pulp sheets and the spacers suitably arranged therebetween, the steeping press was filled with the mercerizing (caustic alkali) solution. The sheets were steeped for an appropriate time, for example 30 minutes to 1 hour, at the end of which the steeping liquor was discharged from the tank. Thereafter, the piston was actuated, for example through a screw or hydraulic means, and the excess liquid expressed from the sheets. When the desired excess caustic soda had been removed from the sheets, the piston was retracted and the bundles of sheets were removed from the tank manually by workers who placed them on carriers in order to compare the weight of the mercerized sheets with the weight of the alpha-cellulose employed. In general, the ratio of the treated sheets to the weight of the alpha-cellulose employed was 3:1.

An object of this invention is to provide a new and improved steeping press.

Another object of this invention is to provide a steeping press having means for automatically discharging the treated sheets from the press.

Other and additional objects of the invention will become apparent hereinafter.

The objects of this invention are accomplished, in general, by providing a steeping press formed in two sections, one of said sections being fixed and open at the rear end thereof, and the second section being open at the front thereof and mov-

2

able so that the open ends of the two sections can be brought into abutting relationship. The press is provided with a carrier carrying a platen which extends in the tank and serves as a support against which the sheets of pulp are compressed by the action of a piston in the fixed tank section. The carrier from which the platen is suspended is independently movable so that the platen can be positioned to receive the pressure during the expressing action. Means are also provided to secure the platen in position during the compression action.

A plate is slidably mounted on the edges of the fixed tank section in position to be advanced axially of the tank during the compression stroke of the piston. When the piston is retracted, the plate, which is not secured to the piston, is caused to move rearwardly by the expansion of the pulp sheets. Means are provided on said plate to cooperate with means carried by the supporting platen whereby said plate is secured to said platen and in spaced relationship thereto, with the result that the sheets of pulp are secured between the supporting platen and the plate.

25 A hopper is provided beneath the open end of the fixed tank section. When the movable tank section is in cooperative relationship with the fixed tank section, the former will close the hopper. When the sheets are secured between the supporting platen and plate and the movable tank section is retracted, the hopper is uncovered. The carrier is then caused to move in a direction so that the block of sheets will be disposed over the hopper. The bundle of sheets, by virtue of their weight, detach themselves from the spacers and drop into the hopper, which feeds them to a suitable collection device.

Means are provided to disengage and release the plate from the supporting platen whereby the plate can be returned to its original position in the fixed tank section.

The present invention will be more clearly understood by reference to the following detailed description when taken in connection with the accompanying drawings, in which:

Figure 1 is an elevation of a steeping press embodying the principles of this invention with parts in loading position;

Figure 2 is a plan view of the apparatus shown in Figure 1;

Figures 3 and 4 are enlarged sections taken on the lines 3—3 and 4—4 respectively of Figure 5;

Fig. 3a is a section taken on the line 3a—3a of Fig. 3;

Figures 5, 6 and 7 illustrate the steeping press at various stages of the operation;

Figure 8 is a fragmentary perspective of the operating mechanism for the carrier and the supporting plate carried thereby;

Figure 9 is a section taken on the line 9—9 of Figure 11;

Figure 10 is a section taken on the line 10—10 of Figure 9;

Figure 11 is a section taken on the line 11—11 of Figure 9; and

Figure 12 is a section taken on the line 12—12 of Figure 10.

Referring now to the drawings wherein like reference numerals designate like parts, the reference numeral 1 designates a main fixed tank section which is open at the rear end thereof, and the reference numeral 2 designates an auxiliary tank section which is open at its front end. The auxiliary tank 2 is provided with rollers 3, 3a and 4, 4a adapted to ride on fixed rails 5 and 5a which are supported at one end by uprights 6 and 6a and at the opposite end by a frame 7 surrounding the open end of the tank section 1. The section 2 also carries a grid plate 1a (Fig. 4) to support the cellulose sheets.

A rigid cross-bar or beam 8 is slidably mounted on the rails 5 and 5a. The cross-bar 8 is provided with a screw 9 which is provided with a hand wheel 10 at one end thereof, and the other end thereof is seated in a boss 11 on the outer end wall 12 of the auxiliary tank 2. When the auxiliary tank 2 occupies the position shown in Figure 1, cotter pins 13 and 13a are disposed in holes of the rails 5 and 5a to serve as an abutment or stop for the cross-bar 8 and prevent it from shifting to the left (in Figure 1) when the open ends of the tank sections 1 and 2 are in abutting relationship. An appropriate seal 14, such as a rubber sealing strip, renders the joint between the auxiliary tank section 2 and the fixed tank section 1 liquid-tight. When the cotter pins 13 and 13a are removed, the cross-bar 8 can be retracted on the rails 5 and 5a into the position shown in dotted lines in Figure 2, with the result that the auxiliary tank section 2 can be moved into spaced relationship with the tank section 1, as shown in dotted lines in Figure 2. Thus, the auxiliary tank section 2 can be disposed so that the open end thereof will be in abutting relationship with the open end of the fixed tank section 1, or the auxiliary tank section 2 can be disposed in spaced relationship with respect to the fixed tank section 1.

In the fixed tank section 1, there is provided a piston 15 which is mounted on one end of a piston rod 16 which, in turn, is adapted to be operated in a known manner, such as hydraulically or through a screw, so that the piston 15 can be moved axially of the tank. In the form shown the rod 16 is threaded and is advanced by a gear train 16a which is driven by a belt 16b from a motor 16c. An auxiliary grid 17 is slidably mounted on the side walls of the tank section 1. It is to be noted that the movable auxiliary grid 17 is not secured to the piston 15 and that when the piston is retracted it will not retract such grid 17. As shown in Fig. 3, the grid 17 is in the form of a framework comprising vertical members 17a and horizontal members 17b and 17c.

A carrier 19 provided with rollers 20 and 20a

is adapted to ride on the upper edges of the auxiliary tank section 2 and the fixed tank section 1 when they are disposed in abutting relationship. The carrier 19 is also adapted to ride on rails 18 when the auxiliary tank section is in spaced relationship to the fixed tank section, as shown, for example in Figure 6. The rails 18 are carried by the tank section 2 and are offset to pass the walls of the tank section 1 but register with the top edge of the tank walls to carry the rollers 20 and 20a when the rails are retracted as in Figure 6. The carrier 19 supports an approach platen 21 which is provided with two forwardly extending side rods 22 and 22a which, adjacent their forward ends, are provided with holes 23 and 23a. For reasons which will hereafter appear, the freely movable plate 17 is provided with latch members 24 and 24a adapted to cooperate with the holes 23 and 23a respectively. The latch members 24 and 24a are continuously urged outwardly by springs 25 and 25a. The latch members 24 and 24a are secured to a cam 26 which is adapted to be operated by a cam lever 26' whereby each of the locking members 25 can be removed from the respective hole. For reasons which will become apparent, the holes 23 and 23a are so shaped that the latch members 24 and 24a of the plate 17 will only be secured therein when the plate 17 is moved rearwardly (to the right in Figure 1) during or after the retraction of the piston 15. During the compression stroke of the piston 15, the respective latch members 24 and 24a will not be secured in but will travel through the respective holes 23 and 23a.

The rollers 20 are rotatably mounted on a shaft 35 carried in bosses 36 of a bracket 36' secured to the platen 21. The rollers 20a are rotatably mounted on a shaft 37 rotatably mounted in bearings 38 on brackets 39 appropriately secured to the platen 21.

The carrier 19 is provided with a reversible motor 27. The motor 27 is secured on a bracket 49 which, in turn, is appropriately secured to the top of the movable platen 21. The motor shaft 43 is provided with a pulley 45 which cooperates with a belt 48 trained over a pulley 50 of a speed reducer 52 mounted on a bracket 53 secured to the platen 21. The speed reducer 52 is provided with an output shaft 54 which carries a pinion 55 at each end thereof. Each pinion 55 is adapted to cooperate with a gear 58 which, in turn, is adapted to rotate a shaft 60. Each shaft 60 is rotatably mounted in bearings 62 appropriately secured by bolts 64 on the rear surface of the platen 21. Each of the vertical shafts 60 has secured thereto a gear 66, each of which is adapted to cooperate with a rack 68 on the opposite side walls of the tank section 2 whereby movement of the carrier over the tank is facilitated. It is apparent that upon actuation of the motor 27, the carrier 19 will be moved longitudinally of the press and the platen 21 will be moved axially in the tank.

The forward movement (to the right in Figure 1) of the carrier 19 and the platen 21 is automatically stopped when a finger 28 on the carrier engages an electric switch 29' in the circuit of the motor 27 and which is positioned at the end 70 of the path of travel of the carrier. The backward movement (to the left in Figure 1) of the carrier 19 and the platen 21 is stopped by a finger engaging a switch (not shown) in the motor circuit and which is positioned at the end of the path of travel of the carrier.

As will become apparent, the platen 21 receives the pressure exerted by the piston 15 during the compression operation for removing the excess steeping liquor from the sheets, and means are therefore provided to absorb the pressure exerted on the platen. In the form shown (see Figures 10 and 12), the platen 21 is provided with two pairs of transversely extending movable bolts 70 and 71. The bolts of each pair are adapted to be moved in opposite directions to engage pockets 72 in a strap 29 surrounding the open end of tank 1. In the form shown, movement of the bolts 70 and 71 is obtained through the operation of a hand wheel 30. The hand wheel 30 is secured on one end of the shaft 37, on which is secured a pinion 76. The pinion 76 is adapted to cooperate with a gear 78 at one end of a vertical shaft 80 rotatably mounted in a bearing 82 appropriately secured to the platen 21. A cap 84 is appropriately secured to the platen 21. Two gears 86 and 88 are each keyed to the shaft. The gear 86 is adapted to cooperate with the rack members 90 of the bolts 71, and the gear 88 is adapted to cooperate with the racks 92 provided on the bolts 70. It is apparent that upon manipulation of the hand wheel 30, the bolts 70 and 71 will be actuated so that they will engage the grooves 72 in the strap 29 or be withdrawn from such grooves.

The shaft 37, which is controlled by the operation of the hand wheel 30, also controls clutches for disposing the shafts 60 in and out of driving relationship with the gears 58. To effect this, each gear 58 is provided with a female clutch member 100, and a male clutch member 102 is secured to the shaft 60 through a pin 104 and a slot 106, whereby the clutch member 102 can slide axially of the shaft 60. A spring 108 tends to normally urge the male clutch member 102 into cooperative relationship with the female clutch member 100. Each clutch member 102 is provided with an annular recess, in which there is positioned two rolls 110 rotatably mounted on the opposite ends of a yoke 112. Each yoke 112 is carried at one end of a lever 114, the other end of which is provided with a cam roller 116 cooperating with a cam 118 on the shaft 37. Each lever 114 is pivoted on a pin 120 appropriately secured to the platen 21.

The shaft 37 is also provided with a cam 124 which is adapted to operate a safety switch 126, which will permit the circuit controlling the actuation of the piston 15 to be energized.

The tank section 1 is provided with an inlet of the usual type (not shown) for the introduction of the treating liquid and an outlet 31. It is to be noted that a hopper 32 is provided adjacent the open end of the tank section 1 and that this hopper is closed by the bottom of the tank section 2 when the tank section 2 is in abutting relationship with the fixed tank section 1.

The hopper 32 leads to suitable means (not shown) for receiving the material delivered thereto by the hopper.

A housing 130 is secured to the shaft 35 by wing nuts 132 and to shaft 37 by the collar 134 and the hub 136 of the hand wheel 30.

In operation, the auxiliary tank 2 is advanced toward the tank section 1 until the ends are in abutting relationship and the cotter pins 13 and 13a positioned in place. The bundles of cellulose pulp sheets together with the spacers are then disposed vertically on edge into the tank. At this stage of the operation, the piston 15, the movable plate 17 and the platen 21 are in positions sub-

stantially as shown in Figure 1. The steeping liquor is then introduced into the tank and, after the required quantity thereof has been introduced, the sheets are permitted to soak therein for the required period of time. At the end of the soaking period, the outlet 31 is opened whereby the steeping liquor is drained from the tank. The motor 27 is then started and, as a consequence, the carrier is caused to travel longitudinally of the tank to the right in Figure 1 until it assumes the position shown in Figure 5. At this time, the hand wheel 30 is rotated so that the gears 86 and 88 actuate the respective locking members 71 and 70 so that they will engage the pockets 72 in the strap 29. In addition to securing the locking members 70 and 71 in position, rotation of the hand wheel 30 also actuates the cam mechanisms 116 and 118 to release the clutch between each of the gears 58 and the shaft 60.

Rotation of the shaft 37 also actuates the switch element 126 which permits the circuit which controls the actuation of the piston 15 to be closed. The piston circuit is then closed and, as a consequence, the piston 15 is advanced toward the left as shown in Figure 5, whereby it compresses the pulp sheets to express therefrom the excess steeping liquor. During the compression stroke, the piston 15 carries with it the plate 17, and at the end of the compression stroke of the piston 15 the position of the parts is substantially as shown in Figure 5. At the end of the compression stroke, the piston rod 16 is retracted, with the result that the piston 15 is also retracted to its original position, as shown in Figure 6. Upon the retraction of the piston 15, the sheet bundles expand, causing the plate 17 to be moved to the right in Figure 6. As the plate 17 advances to the right in Figure 6, the latch means 24 and 24a, under the action of the springs 25 and 25a, will be caused to enter into the holes 23 and 23a of the rods 22 and 22a which are rigid with the platen 21. At this stage, the bundles of sheets are disposed between the plate 17 and the platen 21.

The hand wheel 10 is then manipulated so that the screw 9 is moved in a direction to reduce the pressure of the cross-piece 8 on the cotter pins 13 and 13a, after which such cotter pins are removed and the cross-piece withdrawn to the position designated as 8' in Figure 7, and the auxiliary tank section 2 can be moved rearwardly and withdrawn from the fixed tank section 1, whereby the hopper 32 is uncovered.

The motor 27 is then actuated again (its direction of rotation being automatically reversed by suitable contacts not shown) whereby the carrier is caused to return to its original position, at which point the motor automatically stops. At this time, the parts are substantially in the positions shown in Figure 7, and the sheets of pulp disposed above the hopper 32. In this position, the sheets between the platen 21 and the plate 17, detached from the spacers by their own weight, fall into the hopper which directs the sheets to a carrier (not shown) provided beneath the hopper 32. Thereafter, the cam lever 26' is actuated to withdraw the locking means 24 and 24a from the holes 23 and 23a, whereby the plate 17 can be slidably moved to its original position.

If desired, the plate 17 can be released prior to or during the discharging of the sheets.

After complete unloading, the auxiliary tank section 2 is brought back into contact with the tank 1, and the cross-piece 8 is restored to its original position. The cotter pins 13 and 13a are inserted in the holes and the hand wheel 10

is operated so as to press the two tanks strongly together. The plate 17 is then restored to its original position.

Before the motor 27 is actuated to return the carrier to its original position, the hand wheel 30 is operated either prior to or subsequent to the repositioning of the auxiliary tank section 2, whereby the locking elements 70 and 71 are withdrawn from the pockets 72, and the gears 58 secured in driving relationship with the shafts 60 by the respective clutches.

Since it is obvious that various changes and modifications can be made in the above description without departing from the nature or spirit thereof, this invention is not restricted thereto except as set forth in the appended claims.

I claim:

1. A steeping press for steeping cellulose pulp sheets arranged in said press vertically on edge and in bundles which are separated by spacers, comprising a fixed tank section open at its rear end, a movable tank section open at its forward end, means to move said movable tank section toward and away from said fixed tank section, means to secure said tank sections with the open ends thereof in abutting relationship, a piston slidably positioned in the fixed tank section, a movable platen adapted to be disposed adjacent the open end of said fixed section and constitute a support against which the sheets in the tank are pressed by said piston, a plate slidably mounted in said fixed tank section ahead of said piston, means to lock said plate to and in spaced relationship to said platen when the piston is retracted after its compression stroke whereby the sheets are confined between said platen and plate, and a hopper adjacent the open end of said fixed tank section and adapted to be covered by said movable tank section when the ends of said movable section and fixed section are in abutting relationship, said sheets being discharged under their own weight into said hopper when said movable tank section is positioned so that said hopper is not covered thereby and when said platen and plate are disposed over said hopper.

2. A steeping press for steeping cellulose pulp sheets arranged in said press vertically on edge and in bundles which are separated by spacers, comprising a fixed tank section open at its rear end, a movable tank section open at its forward end, said movable tank section having rollers adapted to ride on rails whereby said movable section can be moved toward or away from said fixed section, means to secure said tank sections with the open ends thereof in abutting relationship, a piston slidably positioned in the fixed tank section, a movable platen adapted to be disposed adjacent the open end of said fixed tank section and constitute a support against which the sheets in the tank are pressed by said piston, a plate slidably mounted in said fixed tank section ahead of said piston, means to lock said plate to and in spaced relationship to said platen when the piston is retracted after its compression stroke whereby the sheets are confined between said platen and plate, and a hopper adjacent the open end of said fixed tank section and adapted to be covered by said movable tank section when the ends of said movable section and fixed section are in abutting relationship, said sheets being discharged under their own weight into said hopper when said movable tank section is positioned so that said hopper is not covered thereby and when said platen and plate are disposed over said hopper.

3. A steeping press for steeping cellulose pulp sheets arranged in said press vertically on edge and in bundles which are separated by spacers, comprising a fixed tank section open at its rear end, a movable tank section open at its forward end, said movable tank section having rollers adapted to ride on rails whereby said movable section can be moved into abutting relationship with or away from said fixed section, a cross-piece slidably mounted on said rails rearwardly of said movable tank section, a screw carried by said cross-piece and adapted to engage the rear wall of said movable tank section, means to secure said cross-piece against rearward movement when the open ends of said tank sections are in abutting relationship, a piston slidably positioned in the fixed tank section, a movable platen adapted to be disposed adjacent the open end of said fixed tank section and constitute a support against which the sheets in the tank are pressed by said piston, a plate slidably mounted in said fixed tank section ahead of said piston, means to lock said plate to and in spaced relationship to said platen when the piston is retracted after its compression stroke whereby the sheets are confined between said platen and plate, and a hopper adjacent the open end of said fixed tank section and adapted to be covered by said movable tank section when the ends of said movable section and fixed section are in abutting relationship, said sheets being discharged under their own weight into said hopper when said movable section is positioned so that said hopper is not covered thereby and when said platen and plate are disposed over said hopper.

4. A steeping press for steeping cellulose pulp sheets arranged in said press vertically on edge and in bundles which are separated by spacers, comprising a fixed tank section open at its rear end, a movable tank section open at its forward end, means to move said movable tank section toward and away from said fixed tank section, means to secure said tank sections with the open ends thereof in abutting relationship, a piston slidably positioned in the fixed tank section, a movable platen adapted to be disposed adjacent the open end of said fixed section and constitute a support against which the sheets in the tank are pressed by said piston, a plate slidably mounted in said fixed tank section ahead of said piston, a pair of spring-pressed latching elements carried by said plate, a pair of rods secured to and extending forwardly of said platen, each rod having a hole adjacent the forward end thereof and adapted to be engaged by one of said locking elements only when said plate moves away from said platen after the compression stroke of the piston whereby the sheets are confined between said platen and plate, and a hopper adjacent the open end of said fixed tank section and adapted to be covered by said movable tank section when the ends of said movable section and fixed section are in abutting relationship, said sheets being discharged under their own weight into said hopper when said movable tank section is positioned so that said hopper is not covered thereby and when said platen and plate are disposed over said hopper.

5. A steeping press for steeping cellulose pulp sheets arranged in said press vertically on edge and in bundles which are separated by spacers, comprising a fixed tank section open at its rear end, a movable tank section open at its forward end, means to move said movable tank section toward and away from said fixed tank section,

means to secure said tank sections with the open ends thereof in abutting relationship, a piston slidably positioned in the fixed tank section, a movable platen adapted to be disposed adjacent the open end of said fixed section and constitute a support against which the sheets in the tank are pressed by said piston, a plate slidably mounted in said fixed tank section ahead of said piston, a pair of spring-pressed latching elements carried by said plate, a pair of rods secured to and extending forwardly of said platen, each rod having a hole adjacent the forward end thereof and adapted to be engaged by one of said locking elements only when said plate moves away from said platen after the compression stroke of the piston, whereby the sheets are confined between said platen and plate, cam operated means to disengage said latching elements from said holes, and a hopper adjacent the open end of said fixed tank section and adapted to be covered by said movable tank section when the ends of said movable section and fixed section are in abutting relationship, said sheets being discharged under their own weight into said hopper when said movable tank section is positioned so that said hopper is not covered thereby and when said platen and plate are disposed over said hopper.

6. A steeping press for steeping cellulose pulp sheets arranged in said press vertically on edge and in bundles which are separated by spacers, comprising a fixed tank section open at its rear end, a movable tank section open at its forward end, means to move said movable tank section toward and away from said fixed tank section, means to secure said tank sections with the open ends thereof in abutting relationship, a piston slidably positioned in the fixed tank section, a movable platen adapted to be disposed adjacent the open end of said fixed section and constitute a support against which the sheets in the tank are pressed by said piston, means to lock said platen in position, a plate slidably mounted in said fixed tank section ahead of said piston, means to lock said plate to and in spaced relationship to said platen when the piston is retracted after its compression stroke whereby the sheets are confined between said platen and plate, and a hopper adjacent the open end of said fixed tank section and adapted to be covered by said movable tank section when the ends of said movable section and fixed section are in abutting relationship, said sheets being discharged under their own weight into said hopper when said movable tank section is positioned so that said hopper is not covered thereby and when said platen and plate are disposed over said hopper.

7. A steeping press for steeping cellulose pulp sheets arranged in said press vertically on edge and in bundles which are separated by spacers, comprising a fixed tank section open at its rear end, a movable tank section open at its forward end, means to move said movable tank section toward and away from said fixed tank section, means to secure said tank sections with the open ends thereof in abutting relationship, a piston slidably positioned in the fixed tank section, a carrier adapted to move over the top edges of said tank sections, a platen carried by said carrier and adapted to constitute a support against which the sheets are pressed by said piston, racks on the side walls of said tank sections, gears adapted to mesh with said racks carried on shafts mounted on the rear face of said platen, movable locking elements extending transversely of said platen, pockets on the fixed tank section

adapted to be engaged by said locking elements, means adapted to move said locking elements in or out of locking engagement with said pockets, a plate slidably mounted in said fixed tank section ahead of said piston, means to lock said plate to and in spaced relationship to said platen when the piston is retracted after its compression stroke whereby the sheets are confined between said platen and plate, and a hopper adjacent the open end of said fixed tank section and adapted to be covered by said movable tank section when the ends of said movable section and fixed section are in abutting relationship, said sheets being discharged under their own weight into said hopper when said movable tank section is positioned so that said hopper is not covered thereby and when said platen and plate are disposed over said hopper.

8. A steeping press for steeping cellulose pulp sheets arranged in said press vertically on edge and in bundles which are separated by spacers, comprising a fixed tank section open at its rear end, a movable tank section open at its forward end, means to move said movable tank section toward and away from said fixed tank section, means to secure said tank sections with the open ends thereof in abutting relationship, a piston slidably positioned in the fixed tank section, a carrier adapted to move over the top edges of said tank sections, a platen carried by said carrier and adapted to constitute a support against which the sheets are pressed by said piston, racks on the side walls of said tank sections, gears adapted to mesh with said racks carried on shafts mounted on the rear face of said platen, drive means to rotate said shafts, a clutch between said drive means and each of said shafts, movable locking elements extending transversely of said platen, pockets on the fixed tank section adapted to be engaged by said locking elements, means adapted to move said locking elements in or out of locking engagement with said pockets, means to simultaneously operate said clutches and locking elements, a plate slidably mounted in said fixed tank section ahead of said piston, means to lock said plate to and in spaced relationship to said platen when the piston is retracted after its compression stroke whereby the sheets are confined between said platen and plate, and a hopper adjacent the open end of said fixed tank section and adapted to be covered by said movable tank section when the ends of said movable section and fixed section are in abutting relationship, said sheets being discharged under their own weight into said hopper when said movable tank section is positioned so that said hopper is not covered thereby and when said platen and plate are disposed over said hopper.

9. A steeping press for steeping cellulose pulp sheets arranged in said press vertically on edge and in bundles which are separated by spacers, comprising a fixed tank section open at its rear end, a movable tank section open at its forward end, means to move said movable tank section toward and away from said fixed tank section, means to secure said tank sections with the open ends thereof in abutting relationship, a piston slidably positioned in the fixed tank section, actuating mechanism for said piston, a carrier adapted to move over the top edges of said tank sections, a platen carried by said carrier and adapted to constitute a support against which the sheets are pressed by said piston, racks on the side walls of said tank sections,

gears adapted to mesh with said racks carried on shafts mounted on the rear face of said platen, drive means to rotate said shafts, a clutch between said drive means and each of said shafts, movable locking elements extending transversely of said platen, pockets on the fixed tank section adapted to be engaged by said locking elements, means adapted to move said locking elements in or out of locking engagement with said pockets, means to simultaneously operate said clutches and locking elements, said means also controlling the actuating mechanism for said piston, a plate slidably mounted in said fixed tank section ahead of said piston, means to lock said plate to and in spaced relationship to said platen when the piston is retracted after its compression stroke whereby the sheets are confined between said platen and plate, and a hopper adjacent the open end of said fixed tank section and adapted to be covered by said mov-

able tank section when the ends of said movable section and fixed section are in abutting relationship, said sheets being discharged under their own weight into said hopper when said movable tank section is positioned so that said hopper is not covered thereby and when said platen and plate are disposed over said hopper.

GASTON JORIS.
